UNITED STATES PATENT OFFICE.

ISRAEL BOGDANOFF, OF PHILADELPHIA, PENNSYLVANIA.

DESIGN FOR A CLOCK-CASE.

41,604.

Specification for Design.

Patented July 25, 1911.

Application filed April 29, 1911. Serial No. 624,265. Term of patent 7 years.

To all whom it may concern:

Be it known that I, ISRAEL BOGDANOFF, a citizen of the United States, residing at Philadelphia, in the county of Philadelphia and State of Pennsylvania, have invented a new, original, and ornamental Design for Clock-Cases, of which the following is a specification, reference being had to the accompanying drawing, forming a part thereof.

The figure is an elevation of a clock case, showing my new design.

I claim:

The ornamental design for a clock case, as shown.

ISRAEL BOGDANOFF.

Witnesses:

WILLIAM T. WHEELER,
M. ELLEN CLEMMER.
